UNITED STATES PATENT OFFICE

YOUNG HO KOUN, OF NEW YORK, N. Y.

DIRIGIBLE HELICOPTER

Application filed July 10, 1928. Serial No. 291,586.

My invention relates to improvements in flying machines and the objects of my improvement are to provide a flying machine suitable for landing upon land or water.

6 It is a further object of my invention to provide a hydrogen tank serving the double purpose of acting as a reservoir for gas to fill inflatable bags and as a pontoon for landing in water; and to also provide wheels 10 for landing upon the ground.

It is a still further object of the invention to utilize the inflatable bags to effect landing of the craft by utilization of inflated gas bags in conjunction with the power units 16 of the craft.

Additional objects, advantages and features of invention will be apparent from the following description considered in conjunction with the accompanying drawings, 20 wherein:

Figure 1 is a top plan view of my dirigible helicopter;

Figure 2 is an enlarged front elevation, a portion of the wings being broken away; and

25 Figure 3 is a side elevation of the hand lever for controlling the position of the motors.

In carrying out my invention I provide a craft having main wings 1 and 2 extending laterally and an auxiliary upper wing 3, this latter wing being of less lateral dimension than the wings 1 and 2, but of greater longitudinal dimension so as to overlie the major portion of the fuselage.

35 The wing 3 has an aperture 3^a, and immediately beneath this aperture is mounted a motor 4. The motor 4 includes a propeller 5, adapted to cooperate with other motors 6, 7, of the craft, to effect propulsion of the craft 40 forwardly, or upwardly, as will be explained more fully hereinafter.

The wings 1 and 2 are likewise provided with apertures 6 and 7, respectively, and motors 8 and 9 are suitably mounted beneath the apertures 6 and 7. The motors 8 and 9 include propellers 10 and 11, which are disposed immediately beneath the apertures 6 and 7, as shown.

45 The motors 8 and 9 are each pivoted between uprights 12 rising from the framework

13 in such manner that the longitudinal axis of the motors may be adjusted to assume either a vertical or horizontal position. When the motors are adjusted to a vertical position they will cause the craft to rise vertically, and when adjusted to a horizontal position, the motors will draw the craft forwardly. The motor 4 is likewise mounted between uprights 12^a and is adjustable from a vertical to a horizontal position.

55 In order to adjust the motors 8 and 9 from a vertical to a horizontal position, or vice versa, the motors 8 and 9 include a shaft 14 having a crank 15. One end of a link 16 is attached to the crank, the opposite end of the 60 link being connected to a hand lever 17. It will be apparent that by manipulating the hand lever 17, the motors 8 and 9 will be rocked to assume the position desired. The motor 4 is independently controlled and may 65 embody any suitable operating means.

Upon the main wings 1 and 2 are secured a series of gas bags 18, connected by tubes 19, the tubes 19 being connected to a compression tank 20, as shown. The tank 20 is suitably 75 mounted beneath the fuselage 21, and functions as a pontoon for floating the craft when disposed upon a body of water.

The craft also embodies landing wheels 22, suitably braced by struts 23, 24 and 25.

80 The gas bags 18 may have any shape desired, but as shown, are elliptical and somewhat flattened. The bags are secured snugly to the wing covering so that air cannot get between them and the wings.

85 Shock absorbing cushions 26 are disposed between the motors and frame as shown and a similar cushion 27 is positioned between the fuselage and the tank 20. These cushions are preferably formed from rubber although 90 it will be apparent that springs may be substituted therefor.

In operation of my craft, in the event that it is desired to make a straight upward rise, the motors 4, 8 and 9 are adjusted to assume 95 a vertical position with their respective propellers disposed immediately beneath respective openings of the wings. The motors being in operation, the craft will be raised vertically upward due to the "pull" set up by the 100

propellers. After the craft has assumed a sufficient height, the motors are moved to their horizontal positions, and the craft will be drawn forwardly. The inflated bag elements will tend to stabilize and buoy the craft during adjustment of the motors from one position to the other.

I claim:

- 10 1. A flying machine comprising main wings, an auxiliary wing above said main wings, all of said wings having openings, a motor beneath each of said openings, said motors having a propeller, means for rotating said motors upon horizontal axis, gas bags mounted upon said wings, a fuselage beneath the main wings, a gas tank beneath said fuselage, tubes connecting said gas bags and said tank and landing wheels beneath said tank.
- 15 2. A flying machine comprising main wings, an auxiliary wing above said main wings, all of said wings having an opening therein, a motor beneath each of said openings, said motors having a propeller, means for simultaneously oscillating the motors disposed beneath the openings of said main wings, and independent means for oscillating the motor disposed beneath the opening of said auxiliary wing, gas bags mounted upon said main wings, a fuselage beneath the main wings, a gas tank beneath said fuselage, tubes connecting said gas bags and said tank, and landing wheels beneath said tank.
- 20 3. In a flying machine, main wings, an auxiliary wing above said main wings, all of said wings having an opening therein, a fuselage including a frame work disposed on opposite sides thereof providing motor mounting means, dirigible motors horizontally mounted in said means and positioned beneath the openings in said main wings, a crank shaft connecting said motors, manual means for simultaneously oscillating said motors, a dirigible motor rockably supported beneath the opening of said auxiliary wing and independent means for rocking said motor.
- 25 4. In a flying machine, main wings, an auxiliary wing above said main wings, all of said wings having an opening therein, a fuselage including a frame work disposed on opposite sides thereof providing motor mounting means, dirigible motors horizontally mounted in said means and positioned beneath the openings in said main wings, a crank shaft connecting said motors, manual means for simultaneously oscillating said motors, a dirigible motor rockably supported beneath the opening of said auxiliary wing and independent means for rocking said motor.
- 30 5. In a flying machine, main wings, an auxiliary wing above said main wings, all of said wings having an opening therein, a fuselage including a frame work disposed on opposite sides thereof providing motor mounting means, dirigible motors horizontally mounted in said means and positioned beneath the openings in said main wings, a crank shaft connecting said motors, manual means for simultaneously oscillating said motors, a dirigible motor rockably supported beneath the opening of said auxiliary wing and independent means for rocking said motor.
- 35 6. In a flying machine, main wings, an auxiliary wing above said main wings, all of said wings having an opening therein, a fuselage including a frame work disposed on opposite sides thereof providing motor mounting means, dirigible motors horizontally mounted in said means and positioned beneath the openings in said main wings, a crank shaft connecting said motors, manual means for simultaneously oscillating said motors, a dirigible motor rockably supported beneath the opening of said auxiliary wing and independent means for rocking said motor.
- 40 7. In a flying machine, main wings, an auxiliary wing above said main wings, all of said wings having an opening therein, a fuselage including a frame work disposed on opposite sides thereof providing motor mounting means, dirigible motors horizontally mounted in said means and positioned beneath the openings in said main wings, a crank shaft connecting said motors, manual means for simultaneously oscillating said motors, a dirigible motor rockably supported beneath the opening of said auxiliary wing and independent means for rocking said motor.
- 45 8. In a flying machine, main wings, an auxiliary wing above said main wings, all of said wings having an opening therein, a fuselage including a frame work disposed on opposite sides thereof providing motor mounting means, dirigible motors horizontally mounted in said means and positioned beneath the openings in said main wings, a crank shaft connecting said motors, manual means for simultaneously oscillating said motors, a dirigible motor rockably supported beneath the opening of said auxiliary wing and independent means for rocking said motor.

In testimony whereof, I hereby affix my signature.
